(57) **CLAIM**

The ornamental design for one piece assembly of container and utensil, as shown and described.

DESCRIPTION

FIG. 1 is a perspective view of an assembly of container and utensil showing our new design;

FIG. 2 is a top plan view thereof;

FIG. 3 is a bottom plan view thereof;

FIG. 4 is an elevational view taken from one side thereof;

FIG. 5 is a front elevational view thereof;

FIG. 6 is an elevational view taken from the other side thereof; and,

FIG. 7 is a rear elevational view thereof.
